UNITED STATES PATENT OFFICE

CHARLES H. CAMPBELL, OF WATERTOWN, NEW YORK.

CUSHIONING DEVICE FOR TYPE-BEDS.

SPECIFICATION forming part of Letters Patent No. 380,182, dated March 27, 1888.

Application filed June 15, 1887. Serial No. 241,336. (No model.)

To all whom it may concern:

Be it known that I, CHARLES H. CAMPBELL, of Watertown, in the county of Jefferson, in the State of New York, have invented new and useful Improvements in Cushioning Devices for Type-Beds, of which the following, taken in connection with the accompanying drawings, is a full, clear, and exact description.

This invention relates to the class of cylinder-presses which have a reciprocating type-bed under the impression-cylinder. In this class of printing-presses it is necessary to provide suitable means for overcoming the momentum of the type-bed at the end of its stroke and assisting the actuating mechanism of the press in starting the type-bed in its retrograde movement. For this purpose there are usually employed cushions or springs of different kinds, which in some instances consist of a piston moving under the resistance of compressed air in a cylinder, and in other cases the springs are of the form of helical wire coils which resist the movement of pivoted arms arranged to receive the impact of the type-bed at the end of the stroke thereof. It is this latter species of type-bed cushioning and repelling devices to which my present invention pertains.

The invention consists in improved devices for readily releasing the type-bed from the force of the repelling-spring when it is required to turn the press mechanism over either center by hand, all as hereinafter more fully described, and specifically set forth in the claims.

In the annexed drawings, Figures 1 and 2 are side views taken immediately at the side of the repelling-arm of a type-bed cushioning and repelling device embodying my improvements and showing the same in two of its operative positions. Fig. 3 is an end view of the same. Fig. 4 shows the repelling-arm released from the force of the main resisting-springs. Fig. 5 is an inner side view of the coupling portion of the repelling-arm. Fig. 6 is a detached plan view of the main resisting-springs; and Fig. 7 is a transverse section on line xx , Fig. 4.

Similar letters of reference indicate corresponding parts.

A represents a portion of the side frame of the press, F the usual cross-stay, and B the end portion of the reciprocating type-bed,

which may be driven in any suitable or well-known manner, and therefore the actuating-gears need not be shown here.

55

C denotes the spring-actuated cushioning and repelling arm, two of which are usually arranged, respectively, at opposite sides of the end of the press-frame, said arms being rigidly secured to a horizontal shaft, g, extended across the base of the press-frame and journaled in the sides thereof. The upper end of each of said arms has pivoted to it the roller t, which, during the approach of the type-bed B to the end of its stroke, runs onto one of the usual 65 shoes, s, which project from the end of the type-bed, as shown in Figs. 1 and 2 of the drawings.

At the side of the arm C, I place a lever, D, pivoted to the shaft g, and connected with the cross-stay F of the press-frame by a spring-coupling, I, consisting of rods b b, each connected at one end to the cross-stay F and extending through a yoke, c, and having a yoke, c', secured to their free ends, and a rod, b', connected at one end to the lever D above the pivot thereof, and extending through the yoke c' and secured to the yoke c between the rods b b, and springs d d d are interposed between the said yokes, as illustrated in Fig. 6 of the drawings.

75

In an eye extending transversely through the arm C is journaled a stud-pin, i, to the ends of which and respectively at opposite sides of the arm are rigidly secured the dog f 85 and the latch l. The lever D is provided with a shoulder, a, and an abutment, n, which latter is adapted to support the arm C when in its normal position, as shown in Fig. 1 of the drawings, and the shoulder a is in such a position and the dog f of such a shape and length as to allow said dog to drop into engagement with the said shoulder when the arm C rests against the abutment n, and thus the arm and lever are locked together to act as if formed 90 in one piece and receive jointly the force of the spring-coupling I, which draws the lever D, with the arm C locked thereon, toward the end of the type-bed B, and a prop, L, secured to the base of the press-frame and encountered 95 by the lever D in its aforesaid movement, serves to support said lever and arm in their normal position.

To the arm C is connected a rod, r, the free

100

end of which slides through a bar, *u*, rigidly secured to the press-frame, and on this bar is mounted a spiral spring, *e*, which is compressed between the bar *u* and the coupling of the rod *r* on the arm *C*, and serves to normally hold the said arm resting against the abutment *n* on the lever *D*, and consequently the dog *f* is normally in engagement with the shoulder *a* and the arm and lever normally locked together.

In the approach of the type-bed *B* to the end of its stroke the shoe *s* engages the roller *t* and crowds back the arm *C* in opposition to the resistance of the spring-coupling *I*, and this resistance overcomes the momentum of the type-bed *B* and assists the same in its reverse movement. When it is desired to move the press mechanism over the center by hand, the repelling-arm *C* can be liberated from the resistance of the spring-coupling *I* by raising the latch *l*, which throws the dog *f* out of engagement with the shoulder *a* of the lever *D*. The arm *C* is then comparatively free to swing back and forth. The only resistance to be overcome in its movement in one direction is that received from the spring *e*, and this is insignificant, it being merely sufficient to throw the arm *C* onto the abutment *n* of the lever *D* when the type-bed is moved away from the roller *t* of the said arm.

Along the side of the press-frame *A*, I extend a shaft, *O*, journaled in suitable bearings secured to said frame, and to this shaft I attach an arm, *P*, which reaches with its free end under the latch *l*, and is provided with a vertical chambered sleeve, *P'*, in which is fitted to slide a pin, *v*, which is supported with its head normally above the top of the sleeve by means of a spiral spring seated in the chamber of the sleeve.

By turning the shaft *O* the free end of the arm *P* is raised, so as to cause the pin *v* to lift the latch *l* and thus throw the dog *f* out of engagement with the shoulder *a* of the lever *D* when desired to liberate the arm *C* from the resistance of the spring-coupling *I*. The shaft *O* may be turned either by the pressure of the attendant's foot onto a treadle secured to the shaft or by a suitable hand-lever, *m*, attached to said shaft.

The spring support of the pin *v* on the arm *P* is necessary for this reason, viz: If the shaft *O* were partially turned and the pin *v* raised while the arm *C* and lever *D* were locked together and in operating position, as shown in Fig. 2 of the drawings, the return of the arm *C* to its normal position would cause the latch *l* and pin *v* to collide and break one or the other of said parts if the pin *v* were not capable of yielding to such contact.

I do not claim, broadly, a spring-actuated repelling-arm arranged to receive the impact of the type-bed at the end of its stroke, as I am aware the same is not new; but

What I do claim as my invention is—

1. In combination with the press-frame, reciprocating type-bed, and the movable cushioning-arm arranged to receive the impact of the type-bed at the end of its stroke, a repelling-spring connected with the said cushioning-arm by a coupling adapted to release the arm from the force of said spring, substantially as and for the purpose set forth. 65

2. In combination with the press-frame, reciprocating type-bed, and the movable cushioning-arm arranged to receive the impact of the type-bed at the end of its stroke, a type-bed repelling-spring, a lever connected to said spring, and a coupling adapted to connect and disconnect the cushioning-arm to and from the said lever, substantially as and for the purpose specified. 75

3. In combination with the press-frame *A*, reciprocating type-bed *B*, and repelling-arm *C*, the lever *D*, provided with the shoulder *a*, the spring-coupling *I*, connecting the lever with the press-frame, the spring *e*, opposed to the rearward movement of the arm *C*, and the dog *f*, connected to said arm and adapted to engage the shoulder *a*, substantially as described and shown. 85

4. In combination with the press-frame *A* and type-bed *B*, the shaft *g*, journaled on said frame, the arm *C*, rigidly secured to said shaft, the lever *D*, pivoted on the same shaft and provided with the shoulder *a* and abutment *n*, the stud-pin *i*, journaled in the arm *C*, the dog *f* and latch *l*, rigidly secured to opposite ends of the said stud-pin, the spring-coupling *I*, connecting the lever *D* with the press-frame, and the spring *e*, opposed to the rearward movement of the arm *C*, substantially as described and shown. 95

5. In combination with the press-frame *A*, type-bed *B*, arm *C*, lever *D*, and dog *f*, detachably connecting said arm and lever and provided with the latch *l*, the shaft *O*, arm *P*, projecting from said shaft and reaching under the aforesaid latch, and the spring-supported pin *v*, carried on the free end of the arm *P*, substantially as and for the purpose set forth. 105

In testimony whereof I have hereunto signed my name and affixed my seal, in the presence of two attesting witnesses, at Syracuse, in the county of Onondaga, in the State of New York, this 7th day of June, 1887.

CHARLES H. CAMPBELL. [L. S.]
